UNITED STATES PATENT OFFICE.

ROBERT SCOTT KERR, OF CHICAGO, ILLINOIS, ASSIGNOR TO CHRISTOPHER H. UEBER-ROTH, OF CHICAGO, ILLINOIS.

DESIGN FOR A PLATE OR SIMILAR ARTICLE.

Application filed August 2, 1923. Serial No. 6,929. Term of patent 7 years.

To all whom it may concern:

Be it known that I, ROBERT SCOTT KERR, a citizen of the United States, and resident of Chicago, in the county of Cook and State of Illinois, have invented a new, original, and ornamental Design for a Plate or Similar Article, of which the following is a specification, reference being had to the accompanying drawing, forming part thereof, which drawing is a plan view of a plate or similar article illustrating my new design.

I claim:

The ornamental design for a plate or similar article, as shown.

ROBERT SCOTT KERR.
